J. P. HOTZ.
ELECTRIC FAN AND CASING.
APPLICATION FILED JULY 8, 1918.

1,301,939.

Patented Apr. 29, 1919.

Inventor:
John P. Hotz,
by his attorney
Harold S. Gooding

UNITED STATES PATENT OFFICE.

JOHN P. HOTZ, OF WATERTOWN, MASSACHUSETTS.

ELECTRIC FAN AND CASING.

1,301,939.

Specification of Letters Patent. Patented Apr. 29, 1919.

Application filed July 8, 1918. Serial No. 243,993.

To all whom it may concern:

Be it known that I, JOHN P. HOTZ, a subject of the Emperor of Austria, residing at Watertown, in the county of Middlesex and 5 State of Massachusetts, have invented new and useful Improvements in Electric Fans and Casings, of which the following is a specification.

This invention relates to a useful and 10 ornamental device particularly adapted to be used in limousine automobiles, the object of the invention being to provide a convenient means for cooling the interior of a limousine body.

15 The device is so constructed that when a switch is operated to start the rotation of a fan a pair of doors will be automatically opened in order that the air from the fan may be directed without obstruction into the 20 interior of the car body and when the circuit is broken the fan will stop rotating and the doors will be automatically closed so as to present a neat and ornamental appearance.

The invention consists in the combination 25 and arrangement of parts set forth in the following specification and particularly pointed out in the claims thereof.

Referring to the drawings:

Figure 1 is a front elevation of my im- 30 proved electric fan and casing with the doors of the casing closed.

Fig. 2 is a sectional elevation taken on line 2—2 of Fig. 1.

Fig. 3 is a sectional underneath plan taken 35 on line 3—3 of Fig. 1, partly in section, of the mechanism for operating the switch and doors with the cap which incloses the said mechanism removed and the doors open.

Like numerals refer to like parts through- 40 out the several views of the drawings.

In the drawings, 5 is the casing, provided 45 with a chamber 6 in which is located a rotary fan 7 which is fast to the shaft 8 of an electric motor 9. The electric motor is driven by batteries connected thereto by wires 10 and 11 which are connected to contact plugs 12 and 13, respectively. The contact plugs 12 and 13 are located in a block 14 of insulating material which is clamped to the bottom 50 of the casing by a bracket 15.

A switch pin 16 is slidably mounted in a bracket 17 fast to the casing and projects through one side of the bracket 15 and through the insulating block 14 and contact 55 plugs 12 and 13 when the electric circuit is

closed. Said switch pin is provided with a head 18 and a spring 19 encircles said switch pin bearing at one end against the bracket 17 and at the other end against the head 18 of said pin. In Fig. 3 the switch pin is shown as projecting through both of the contact plugs 12 and 13, thus closing the electric circuit so that the fan will be at that time rotated by the motor.

A pair of doors 20 and 21 are fastened to 65 shafts 22 and 23 rotatably mounted on the casing 5. These doors serve to open and close the chamber 6. On the lower ends of the shafts 22 and 23 are fastened pinions 24 and 25 which engage rack bars 26 and 27 respectively. The rack bar 26 is guided in brackets 28, 29 and 30 and the rack bar 27 is guided in brackets 31, 17 and 30. These rack bars engage a pinion 32 on opposite sides thereof.

75 The pinion 32 is fast to a vertical stud 33 which is rotatably mounted in the bracket 30 and terminates at its lower end in a crank 34. A collar 35 is fastened to the stud 33 and bears against the under side of a cap plate 36 which is fastened to the bottom of the casing and incloses the mechanism for rotating the doors and operating the switch hereinbefore described.

The left hand end of the rack 26 (Fig. 3) 85 is adapted to engage the switch pin 16 to move the same toward the left to close the circuit.

The general operation of the device hereinbefore specifically described is as follows: 90 Assuming the parts to be in the relative positions shown in the drawings, Fig. 3, it will be noted that the switch pin 16 is in position to close the electric circuit by joining the contact plugs 12 and 13 together and the electric fan 7 is then being rotated by the motor 9, and at this time the doors are open.

If it is desired to stop the fan and close the doors, this may be done simultaneously 100 by giving the stud 33 a quarter rotation by means of the crank handle 34, thus rotating the pinion 32 and moving the rack 27 toward the left and the rack 26 toward the right (Fig. 3). As said racks move away 105 from each other, the pinions 24 and 25 are rotated in the proper direction to close the doors and simultaneously the rack 26 moving toward the right allows the spring 19 to move the switch pin 16 toward the right and 110

out of contact with the contact plug 12, whereupon the electric circuit will be opened and the fan will stop its rotation.

The doors 20 and 21 are preferably provided with openings 43 and 44 which allow air to pass out of the casing freely. The casing is also provided with perforations or slits 37 so that the air has free circulation from the interior of the casing to the interior of the automobile body. In addition the casing is provided with a note pad 38 and a mirror 39 which slide vertically into the back part of the casing. As a further means of rendering the device useful as well as ornamental a counter 40 is provided for the months and days of the month and another counter 41 for the years. A watch 42 is also mounted upon the central portion of the casing above the doors, the whole device thus being made very useful and ornamental.

Having thus described my invention, what I claim and desire to secure by Letters Patent is:

1. A device of the character described having, in combination, a casing provided with a chamber, a door to said casing opening out of said chamber, a fan in said chamber, an electric motor adapted to rotate said fan, a switch in electric circuit with said motor and means to simultaneously open said door and actuate said switch to close said circuit and vice versa.

2. A device of the character described having, in combination, a casing provided with a chamber, a shaft rotatably mounted on said casing, a door fast to said shaft and opening out of said chamber, a fan in said chamber, an electric motor adapted to rotate said fan, a switch in electric circuit with said motor, a pinion fast to said shaft, and a rack-bar slidable on said casing and engaging said pinion, said rack-bar adapted to engage said switch and move the same to close said circuit, whereby said door may be opened and said circuit closed simultaneously.

3. A device of the character described having, in combination, a casing provided with a chamber, a shaft rotatably mounted on said casing, a door fast to said shaft and opening out of said chamber, a fan in said chamber, an electric motor adapted to rotate said fan, a pin slidably mounted upon said casing and constituting a switch in electric circuit with said motor, a pinion fast to said shaft, and a rack-bar slidable on said casing and engaging said pinion, said rack bar adapted to engage said pin and move the same to close said circuit, whereby said door may be opened and said circuit closed simultaneously.

4. A device of the character described having, in combination, a casing provided with a chamber, a shaft rotatably mounted on said casing, a door fast to said shaft and

opening out of said chamber, a fan in said chamber, an electric motor adapted to rotate said fan, a switch in electric circuit with said motor, a pinion fast to said shaft, a rack-bar slidable on said casing and engaging said pinion, said rack-bar adapted to engage said switch and move the same to close said circuit, and means to impart a reciprocatory motion to said rack-bar whereby said door may be opened and said circuit closed simultaneously. 70

5. A device of the character described having, in combination, a casing provided with a chamber, a shaft rotatably mounted on said casing, a door fast to said shaft and opening out of said chamber, a fan in said chamber, an electric motor adapted to rotate said fan, a pin slidably mounted upon said casing and constituting a switch in electric circuit with said motor, a pinion fast to said shaft, a rack-bar slidable on said casing and engaging said pinion, said rack-bar adapted to engage said pin and move the same to close said circuit, a spring adapted to move said pin in the opposite direction to open said circuit, and means to impart a reciprocatory motion to said rack-bar, whereby said door may be opened and said circuit closed simultaneously and vice versa. 85

6. A device of the character described having, in combination, a casing provided with a chamber, a pair of doors on said casing opening out of said chamber, a fan in said chamber, an electric motor adapted to rotate said fan, a switch in electric circuit with said motor, a pair of shafts rotatably mounted upon said casing to which shafts said doors are fastened, a pinion fast to each of said shafts, a pair of rack bars engaging said pinions, one of said rack bars adapted to engage said switch to close said circuit and means to simultaneously move said rack bars in opposite directions whereby said doors may be opened and said switch closed simultaneously. 95

7. A device of the character described having, in combination, a casing provided with a chamber, a pair of doors on said casing opening out of said chamber, a fan in said chamber, an electric motor adapted to rotate said fan, a switch in electric circuit with said motor, a pair of shafts rotatably mounted upon said casing to which shafts said doors are fastened, a pinion fast to each of said shafts, a pair of rack bars engaging said pinions, one of said rack-bars adapted to engage said switch to close said circuit, a spring adapted to operate said switch to break said circuit, and means to simultaneously move said rack bars in opposite directions whereby said doors may be opened and said switch closed simultaneously and vice versa. 110

8. A device of the character described having, in combination, a casing provided with

a chamber, a pair of doors on said casing opening out of said chamber, a fan in said chamber, an electric motor adapted to rotate said fan, a switch in electric circuit with said motor, a pair of shafts rotatably mounted upon said casing to which shafts said doors are fastened, a pinion fast to each of said shafts, a pair of rack bars engaging said pinions, one of said rack bars adapted to engage said switch to move the same to close said circuit, a pinion adapted to be engaged by said rack bars

5 on opposite sides thereof, whereby said rack bars may be simultaneously moved in opposite directions and said doors opened 15 and said circuit closed simultaneously.

10 In testimony whereof I have hereunto set my hand in presence of two subscribing witnesses.
